UNITED STATES PATENT OFFICE

MAURICE LACHMAN, OF NEW YORK, N. Y.

SKELETON REENFORCEMENT

Application filed December 28, 1929. Serial No. 417,054.

My invention relates to the construction of open or skeleton grating or metal work and more particularly has to do with the method of producing and the construction of a skeleton reenforcement suitable for use as an imbedded part of the surface of a pavement, an edge of said skeleton work forming a part of the wear surface while the skeleton as a whole is imbedded in and is anchored by the material filling the interstices or openings of the skeleton and practically flush as to its upper or wear surface with the wear edge of the skeleton.

The special object of my invention is to cheapen the production of skeleton metal work or reenforcement from sheet metal strips or bars and is especially useful in the case of skeleton metal work or reenforcement produced from strips or bars bent and united at their bends to form the open work structure.

My invention is carried out by dividing a strip of metal of the desired gage for stiffness on what may be conveniently described as a longitudinal zigzag line, the effect being to produce two strips from a single strip, each section having a substantially flat or uniform edge and an indented edge forming, as to the projecting portions thereof, means for supporting the skeleton upon a suitable foundation.

In carrying out my invention each said section is bent to and fro as will be more particularly hereinafter described and the sections being placed side by side are united at the said bends to form four-sided openings which may be square or lozenge-shaped or otherwise diversified. The bends may be formed at points in the strip coincident with the projecting part of each section or at points coincident with the indentations or recesses and the unions between adjoining strips be made in both cases at the bend. In either case the projections on one edge of each strip will afford feet or supports for the reenforcement.

A further feature of my invention relates to the manner of securing adjoining strips together to prevent displacement of the same with relation to one another during the work

of embodying the reenforcement as a part of the pavement surface. This part of my invention consists in providing the strips with tongues and slots alternately at the bends, the tongues on one strip being adapted to enter a slot in the contiguous strip and to be bent down during the assembly of the strips so as to fasten them together.

The invention further consists in details of construction more particularly hereinafter described and claimed.

In the accompanying drawings:

Fig. 1 is a perspective view of a skeleton grating or reenforcement embodying my invention.

Fig. 2 illustrates the manner of subdividing a metal bar or strip to form two complementary bars each adapted for use in building up the grating.

Fig. 3 illustrates in perspective one of the longitudinal sections of a bar or strip bent preparatory to assembly and union with the complementary or other sub-division bent as shown in Fig. 4.

Fig. 4 illustrates in perspective the complementary element bent to be assembled with the bar disclosed in Fig. 3.

Fig. 5 is a vertical section through adjoining members at the points of bend and union.

Fig. 6 is a perspective view of a modification in which the bends of the divisions are formed to coincide with the recess or indentation in the edge and the projecting portion of the edge lies along the side of the opening and further shows a modification in the manner of fastening adjoining strips together by bars placed against the lower edge coincidently with said recesses.

Fig. 7 shows in perspective a bar or strip and the manner of sub-dividing the same to form a pair of strips each adapted for use in making the grating or skeleton reenforcement Fig. 6.

Fig. 8 shows a bent portion of one of said strips as bent preparatory to assembling and building up.

Fig. 9 is a vertical cross-section through the grating or reenforcement Fig. 6 at the point of union between the strips.

Fig. 10 illustrates in perspective a modification in the manner of utilizing the two longitudinal sections of a bar or strip as component parts of a grating in which the projecting portions of each strip form feet or supports and the bent portions of the skeleton reenforcement comprise a strip of uniform width which is bent and interposed between and united at the bends with the sections of strip to provide a skeleton grating in which the openings are of modified form.

Referring first to Fig. 2, there is shown in full lines one end of a strip of metal 1 which, for the purpose of my invention, I divide 15 longitudinally on the continuous dotted line 2 that may be roughly described as a zigzag line serving to form from the single strip 1 two similar strips each of which is continuous at one edge coinciding with the outer edge of the undivided strip and as to its other edge has projections 3 and indentations or recesses 4 which are complementary in that they are correspondingly shaped and proportioned.

20 When said sections or divisions are reversed in position to bring the straight or undivided edges in the same plane and the strips are bent on transverse lines 5 to the forms indicated respectively in Figs. 3 and 4 and are 25 assembled in contact with one another at the bends as shown in Fig. 1 there results a skeleton structure having a continuous or unbroken upper edge and a broken lower edge the 30 projections of which afford feet or supports for the grating or skeleton. The intermediate parts of each strip are, as shown, of arch shape and afford by the arch the necessary 35 strength between the points of junction of the strips themselves.

40 In practice it is desirable to transport the divisions to the place of use and there assemble them, for which purpose the bending may be done at the place of manufacture of the elements and the strips nested and so transported. In order to afford means for readily 45 uniting the elements or building up the skeleton structure at the place of use I provide slots 6 and struck-up tongues 7 formed in the strips at their alternate bends respectively so that, 50 upon bringing the strips together when placed in the relation indicated by Figs. 3 and 4 taken together, the tongue 7 of one strip may enter the slot 6 of the adjoining strip and be thereafter struck with a tool to bend it 55 down as shown in Figs. 1 and 5 thereby effectually preventing either part from being raised independently of the other.

60 By this feature of my invention the building up of the skeleton reenforcement is particularly facilitated at the place of use as for instance when it is desired to use a skeleton as a component part of the surface of a pavement wherein the continuous upper edge forms a wear surface in conjunction with the 65 filler or composition, whether asphalt, con-

crete or other material, filled in and upon the skeleton or in which it is forcibly imbedded. In either case, as will be well understood by those skilled in the art, any superfluous material is struck off the upper 70 surface to provide a uniform wear surface.

The skeleton thus constructed will be effectually supported by the projections 3 upon its sub-foundation or base and will be prevented from being displaced vertically with 75 relation to the surface filling. Furthermore the surface material in which it is imbedded will be effectually prevented from creeping or sidewise displacement by the projecting 80 feet 3, the recesses at 4 affording the desirable continuity of the surface material so that the same will not be unduly weakened.

For the modified construction illustrated in Fig. 6 I may employ sub-divisions of a metal strip 1 divided on the wavy or zig-zag line 2 as before. In Fig. 7 there is indicated by the transverse dotted lines 5, as in the case of Fig. 2, the position of the bends in each of the two sections, said bends being in this instance coincident with the 85 recessions or indentations as shown also in Fig. 8 illustrating the bent strip.

The union of the strips into a complete grating or skeleton reenforcement as indicated in Fig. 6 results in the reenforcement in which the projecting portions of the cut edge of the strip indicated at 3 form the feet or supports for the skeleton while the narrower portions at their places of incidence are in this instance fastened together and strengthened by 90 transverse rods 8 welded or otherwise secured to their edges and as illustrated more in detail in Fig. 9.

The projections 3 forming the feet located 95 between junctions act, as before explained, as a support fixing the level of the skeleton and also resist creeping or displacement of the material in which the skeleton is imbedded.

Fig. 10 shows how the component parts or 100 sub-divisions of a divided strip like that of Fig. 2 or Fig. 7 may be utilized without bending of the said indented sub-divisions. In this instance the several members each consisting of one of the two divisions are arranged in parallel relation and are spaced 105 apart and united by a bent strip 9 which is of uniform width and approximately of the same width of material as the width of the sub-division at the place of indentation.

110 In either of the cases described it is obvious that by using sub-divisions of a strip sub-divided as described and employed in the manner shown I am enabled to save in weight of material and at the same time produce a skeleton reenforcement which will be 115 useful and effective in its location of use.

120 What I claim as my invention is:

1. A skeleton grating or reenforcement built up of sections of a plate, each section being continuous or straight on one edge and 125

- having complementary projections and intervening recessions at its opposite edge, said plate sections being of general zigzag form throughout their length with the portions 5 thereof having said projections arranged in substantially parallel planes connected by obliquely arranged portions of said plate provided with said recessions, the parallel portions of said plate being attached together.
- 10 2. A skeleton grille, grating or reenforcement consisting of strips of metal rigidly secured together at spaced points thereon, said strips of metal being formed on one edge with a succession of complementary indentations 15 and projections, said projecting portions affording in the completed grating feet or projections for supporting the reenforcement out of contact with a base and serving likewise as a means for preventing the shifting of the 20 structure in the plane of the reenforcement and additional strengthening members extending across and being rigidly connected to said metal strips.
- 25 3. A skeleton grating or reenforcement formed of a series of strips or bars of metal each indented at one edge and substantially straight at the other, said members being bent laterally to the plane of the strip and rigidly secured together at their bends to form 30 successions of openings, the indented edges of said strips or bars extending downwardly to form the support for said grating or reenforcement.
- 35 4. A skeleton grating or reenforcement comprising alternately bent strips secured together at the apexes of the bends therein, said strips being provided with tongues and slots alternately at the bends to facilitate the building 40 up of the reenforcement in the location of use by entering the tongues and bending them down in the slots, said strips being formed with upper surfaces arranged in one plane and with lower surfaces cut away on zigzag 45 lines forming alternate projecting supporting feet and cut-away recesses forming a means of communication between successive pockets formed between said strips.
- 50 5. A skeleton metallic framework formed of metal strips provided on one edge with alternate projections and indentations and on the other edge with substantially straight surfaces, said strips in the completed grating being of zigzag form and secured together at spaced points thereon uniformly selected 55 with respect to said projections and indentations to form a skeleton framework having one face arranged in one plane and the other face provided with uniform and complementary projections and indentations forming alternate feet and transverse passages.
- 60

Signed at New York in the county of New York and State of New York, this 27th day of December, A. D. 1929.

MAURICE LACHMAN.
